FIG. 13D

A diagram illustrating cardinal directions. It features a central vertical line with a horizontal crossbar. An arrow pointing upwards from the crossbar is labeled 'UP'. An arrow pointing downwards from the crossbar is labeled 'DOWN'. The word 'FRONT' is positioned to the left of the vertical line, and the word 'REAR' is positioned to the right. The word 'BACK' is positioned above the 'UP' arrow, and the word 'FRONT' is positioned below the 'UP' arrow.

APPLICATION**

This is a continuation application of International Application No. PCT/JP2020/034879 filed on Sep. 15, 2020 which claims priority from Japanese Patent Application No. 2019-178918 filed on Sep. 30, 2019. The entire contents of the earlier applications are incorporated herein by reference.

TECHNICAL FIELD

Aspects of the disclosure relate to a printer.

BACKGROUND

In a device that performs printing on a tape, replacement and resupply of a tape is performed by attachment and detachment of a cassette accommodating a tape to and from a housing of the device. In such a device, for example, the cassette is placed in a recessed portion provided in the housing.

SUMMARY

In the above-described device, the cassette is mounted on the housing without protruding from the recessed portion. The cassette is provided with a tab for enabling the cassette to be removed from the recessed portion, which may increase a parts count of the cassette and lead to an increase in cost.

Accordingly, aspects of the disclosure provide a printer that may avoid an increase in cost of a cassette attachable to and detachable from a housing of the printer.

In one or more aspects of the disclosure, a printer may include a housing having a first surface having a cassette mounting opening, a print head disposed in the housing and extending toward the cassette mounting opening from an inside of the housing, a platen roller disposed in the housing and facing the print head, and a printing cassette mountable on the housing by insertion to the cassette mounting opening in a first direction.

The first surface may have a first area adjacent to the cassette mounting opening, and a second area adjacent to the cassette mounting opening. The second area may be opposite to the first area with respect to the cassette mounting opening in a second direction orthogonal to the first direction. The first area and the second area may be located upstream from the print head in a direction in which the printing cassette is mounted to the housing.

In a state where the printing cassette is mounted on the housing, a portion of the printing cassette adjacent to the first area may be located outside the housing beyond the first area in the first direction and a portion of the printing cassette adjacent to the second area may be located outside the housing beyond the second area in the first direction.

In one or more aspects of the disclosure, a printer may include a housing having a first surface having a cassette mounting opening, a print head disposed in the housing and extending toward the cassette mounting opening from an inside of the housing, a platen roller disposed in the housing and facing the print head, and a printing cassette mountable on the housing by insertion to the cassette mounting opening in a first direction.

The first surface may have a first area adjacent to the cassette mounting opening, and a second area adjacent to the

2

cassette mounting opening. The second area may be opposite to the first area with respect to the cassette mounting opening in a second direction orthogonal to the first direction. The first area and the second area may be located upstream from the print head in a direction in which the printing cassette is mounted to the housing. In a state where the printing cassette is mounted on the housing, the printing cassette may protrude outside the housing beyond the first area and the second area in the up-down direction.

According to such a configuration, in a state where the printing cassette is mounted on the housing, a particular portion of the printing cassette may be located outside the housing beyond the first surface. Thus, the printing cassette may be held and removed from the housing without a tab. As a result, an increase in cost of the printing cassette may be avoided.

Further, the first area and the second area may be located upstream from the print head in the direction in which the printing cassette is mounted to the housing. Thus, the printing cassette may be held upstream from the print head. As a result, when the printing cassette is removed, interference between the printing cassette and the print head may be reduced.

In one or more aspects of the disclosure, a printer may include a housing having a first surface having a cassette mounting opening, a print head disposed in the housing and extending toward the cassette mounting opening from an inside of the housing, a platen roller disposed in the housing and facing the print head, and a printing cassette mountable on the housing by insertion to the cassette mounting opening in a first direction.

The printing cassette may have a first side-surface and a second side-surface overlapping each other in a second direction orthogonal to the first direction. In a state where the printing cassette is mounted on the housing, at least a portion of the first side-surface and at least a portion of the second side-surface do not overlap the housing in the second direction.

According to such a configuration, in a state where the printing cassette is mounted on the housing, the particular portion of the printing cassette is located outside the housing beyond the first surface. Thus, the printing cassette may be held and removed from the housing without a tab. As a result, an increase in cost of the printing cassette may be avoided.

BRIEF DESCRIPTION OF THE DRAWINGS

FIG. 1A is a schematic perspective view illustrating a state where a cover of a printer body is opened in a printer according to an illustrative embodiment.

FIG. 1B is a schematic perspective view illustrating a state where the cover of the printer body is closed in the printer according to the illustrative embodiment.

FIGS. 2A, 2B, and 2C are schematic perspective views each illustrating a state where a printing cassette is detached from the printer body in the printer according to the illustrative embodiment.

FIGS. 3A, 3B, and 3C are schematic perspective views each illustrating the printing cassette in the printer of FIG. 1A.

FIG. 4A is a schematic rear view of the printing cassette of FIG. 3A.

FIG. 4B is a schematic side view of the printing cassette of FIG. 3A.

FIG. 5 is a disassembled schematic perspective view of the printing cassette of FIG. 3A.

FIG. 6A is a schematic perspective view of a first frame portion of the printing cassette of FIG. 3A.

FIG. 6B is a schematic perspective view of a second frame portion of the printing cassette of FIG. 3A.

FIG. 7 is a schematic perspective view illustrating a state where a first case portion of the printing cassette of FIG. 3C is removed.

FIG. 8A is a schematic cross-sectional view taken along line VIIIA-VIIIA of FIG. 4A.

FIG. 8B is a schematic cross-sectional view taken along line VIIIB-VIIIB of FIG. 4B.

FIG. 9 is a perspective view for explaining a path of a to-be-printed tape and a path of an ink ribbon in the printing cassette of FIG. 3A.

FIG. 10A is a schematic cross-sectional view taken along line XA-XA of FIG. 3C.

FIG. 10B is a schematic cross-sectional view taken along line XB-XB of FIG. 3C.

FIG. 10C is a schematic cross-sectional view taken along line XC-XC of FIG. 3C.

FIG. 10D is a schematic cross-sectional view taken along line XD-XD of FIG. 3C.

FIG. 11 is a schematic plan view illustrating the printer body of the printer of FIG. 1A.

FIG. 12 is a schematic view illustrating a state where an output gear and a platen gear are in engagement with each other in the printer of FIG. 1A.

FIG. 13A is a schematic front view illustrating a state where the printing cassette is mounted on the housing of the printer of FIG. 1A.

FIG. 13B is a schematic left side view illustrating a state where the printing cassette is mounted on the housing of the printer of FIG. 1A.

FIG. 13C is a schematic plan view illustrating a state where the printing cassette is mounted on the housing of the printer of FIG. 1A.

FIG. 13D is a schematic left side view illustrating a state where the printing cassette is mounted on the housing of the printer of FIG. 1A.

FIG. 13E is a schematic rear view illustrating a state where the printing cassette is mounted on the housing of the printer of FIG. 1A.

FIGS. 14A and 14B are schematic perspective views each illustrating a state where a printing cassette is detached from a printer body in a printer according to another illustrative embodiment different from the illustrative embodiment illustrated in FIG. 1A.

FIG. 15 is a disassembled schematic perspective view of the printing cassette in the printer of FIG. 14A.

FIG. 16 is a schematic plan view illustrating the printer body of the printer of FIG. 14A.

FIG. 17 is a schematic view illustrating a state where an output gear and a platen gear are in engagement with each other in the printer of FIG. 14A.

DETAILED DESCRIPTION

1. First Illustrative Embodiment

[1-1. Configuration]

A printer 1 illustrated in FIGS. 1A and 1B includes a printing cassette 10 and a printer body 100. The printer 1 is a device that performs printing on a tape-shaped printing medium.

In the illustrative embodiment, an axial direction of an output gear 18 of the printing cassette 10 and an axial direction of a platen gear 104 of the printer body 100 are

defined as an up-down direction. A direction in which the output gear 18 and an input spool 16 are disposed side by side (i.e., a direction in which the platen gear 104 and a drive shaft 105 are disposed side by side) is referred to as a front-rear direction. A direction orthogonal to both the up-down direction and the front-rear direction is referred to as a left-right direction.

<Printer Body>

The printer body 100 includes a housing 110, a cover 120, and a pressing member 121 provided at the cover 120.

The housing 110 has a first surface 111 having a cassette mounting opening 110A. The first surface 111 constitutes an upper surface of the housing 110. The printing cassette 10 is configured to be placed in the housing 110 in a state where the cover 120 (refer to FIG. 1A) is opened.

The cover 120 is swingably attached to the housing 110. The cover 120 is configured to be openable and closable with respect to the housing 110 and cover the printing cassette 10 from the side opposite to the side where the housing 110 is disposed (i.e., from above). The cover 120 is in contact with the first surface 111 in the closed state.

In a state where the printing cassette 10 is placed in the housing 110, an upper end of the printing cassette 10, that is, an upper end of a pressed portion 50 in the illustrative embodiment, is located above the first surface 111.

In a state where the cover 120 is closed (refer to FIG. 1B), the pressing member 121 presses the printing cassette 10 downward in the housing 110. In the illustrative embodiment, as illustrated in FIG. 1B, a state where the printing cassette 10 is placed in the housing 110 and the cover 120 is closed may be defined as a state where the printing cassette 10 is mounted on the printer body 100.

Further, as illustrated in FIGS. 2A, 2B, and 2C, the printer body 100 includes a cassette insertion portion 101, a print head 102, a platen roller 103, the platen gear 104, and the drive shaft 105.

(Cassette Insertion Portion)

The cassette insertion portion 101 may be a recessed portion where the printing cassette 10 is to be placed. The cassette insertion portion 101 has a function of positioning the printing cassette 10.

The cassette insertion portion 101 is provided at the housing 110. Specifically, the cassette insertion portion 101 defines a space into which a portion of the printing cassette 10 is to be inserted, together with the cassette mounting opening 110A. The cassette insertion portion 101 may be a portion of the first surface 111 recessed downward and overlapping the cassette mounting opening 110A.

(Print Head)

The print head 102 is disposed in the cassette insertion portion 101. The print head 102 has a plurality of heating elements, heat generation of which are individually controlled.

The print head 102 is a plate-shaped member disposed such that a thickness direction thereof is parallel to the front-rear direction. The print head 102 extends in the up-down direction from the inside of the housing 110 (i.e., the cassette insertion portion 101) toward the cassette mounting opening 110A.

(Platen Roller)

A rotation axis L1 of the platen roller 103 is parallel to the up-down direction. The platen roller 103 is disposed facing the print head 102 in the cassette insertion portion 101. The platen roller 103 is swingable in a direction toward or away from the print head 102.

(Platen Gear)

The platen gear **104** is coupled to the platen roller **103**. In the illustrative embodiment, a rotation axis **L2** of the platen gear **104** is coaxial with the rotation axis **L1** of the platen roller **103**. The platen gear **104** is swingable together with the platen roller **103**.

(Drive Shaft)

The drive shaft **105** is to be inserted into the input spool **16**. The drive shaft **105** rotates the input spool **16**.

The drive shaft **105** is disposed in the cassette insertion portion **101**. A rotation axis **L3** of the drive shaft **105** is parallel to the up-down direction. The drive shaft **105** rotates about its rotation axis **L3** by a driving source (e.g., a motor) (not illustrated).

<Printing Cassette>

The printing cassette **10** accommodates a printing medium. The printing cassette **10** is mountable to and removable from the printer body **100**.

The printing cassette **10** is mountable to the housing **110** by insertion to the cassette mounting opening **110A** in the up-down direction. Replacing the printing cassette **10** may achieve resupply of a printing medium and change of a type (e.g., color, material, or others) of the printing medium.

As illustrated in FIGS. 3A, 3B, 3C, 4A, and 4B, the printing cassette **10** includes a case **35** that accommodates a to-be-printed tape **11A**, an ink ribbon **14A**, and others, and the pressed portion **50**. An outer shape of the printing cassette **10** (i.e., a shape of the case **35**) may be a rectangular parallelepiped having sides parallel to the up-down direction, sides parallel to the front-rear direction, and sides parallel to the left-right direction.

The case **35** has a first side-surface **35A**, a second side-surface **35B**, a third side-surface **35C**, and a fourth side-surface **35D**. The first side-surface **35A** constitutes a front surface of the printing cassette **10**. The second side-surface **35B** constitutes a rear surface of the printing cassette **10**. The third side-surface **35C** constitutes a right surface of the printing cassette **10**. The fourth side-surface **35D** constitutes a left surface of the printing cassette **10**.

The first side-surface **35A** and the second side-surface **35B** are orthogonal to the front-rear direction and are located overlapping each other in the front-rear direction. The third side-surface **35C** and the fourth side-surface **35D** are orthogonal to the left-right direction and are located overlapping each other in the left-right direction.

The case **35** includes a first case portion **31**, a first frame portion **32**, a second frame portion **33**, and a second case portion **34**.

The pressed portion **50** may be a portion that receives a pressing force from the pressing member **121** of the printer body **100** in a state where the printing cassette **10** is mounted on the printer body **100**. The pressed portion **50** is exposed through an opening **31B** provided at the upper surface of the case **35**.

As illustrated in FIG. 5, the printing cassette **10** includes a first roll **11**, a first feed spool **12**, a spacer film **13A**, a spacer film **13B**, a second roll **14**, a second feed spool **15**, an input spool **16**, a clutch spring holder **17**, the output gear **18**, the input gear **19**, and an idle gear **20**.

(First Roll)

in the first roll **11**, the to-be-printed tape **11A** on which printing is to be performed is wound around the first feed spool **12**. The first roll **11** has a cylindrical shape having a hollow portion that is defined by an inner peripheral surface of the to-be-printed tape **11A** wound about its axis parallel to the up-down direction. Printing is performed on a surface

of the to-be-printed tape **11A** by the print head **102** of the printer body **100** and the ink ribbon **14A**.

Two spacer films **13A**, **13B** are disposed outside the first roll **11** in the up-down direction such that the spacer films **13A**, **13B** sandwich the first roll **11** therebetween. The spacer film **13A** is disposed between the first roll **11** and the first case portion **31**. The spacer film **13B** is disposed between the first roll **11** and the first frame portion **32**.

(First Feed Spool)

10 The first feed spool **12** is rotatable about its rotation axis **L4**. The first feed spool **12** rotates along with conveyance of the to-be-printed tape **11A** by the platen roller **103** of the printer body **100**, thereby feeding the to-be-printed tape **11A** to the print head **102**.

(Second Roll)

15 In the second roll **14**, the ink ribbon **14A** used for printing on the to-be-printed tape **11A** is wound around the second feed spool **15**.

In a head opening **33B**, the ink ribbon **14A** is laid on the 20 to-be-printed tape **11A** and used for printing performed by the print head **102** therein. The ink ribbon **14A** that has been used for printing is taken up by the input spool **16**. A rotation resistance is applied to the second roll **14** by a clutch spring held by the clutch spring holder **17**. The second roll **14** is 25 disposed such that a portion thereof overlaps the first roll **11** in the up-down direction.

(Second Feed Spool)

The second feed spool **15** is rotatable about its rotation axis **L5**. The rotation axis **L5** of the second feed spool **15** is 30 parallel to the rotation axis **L4** of the first feed spool **12**, that is, parallel to the up-down direction.

The second feed spool **15** rotates along with take-up of the ink ribbon **14A** by the input spool **16**, thereby feeding the ink ribbon **14A** to the print head **102**.

(Input Spool)

The input spool **16** is rotatable about its rotation axis **L6**. The rotation axis **L6** of the input spool **16** is parallel to the rotation axis **L5** of the second feed spool **15**.

The input spool **16** has a cylindrical shape having a 40 hollow portion defined by its inner peripheral surface **16A**. Spline teeth **16B** are provided on the inner peripheral surface **16A** of the input spool **16**. The spline teeth **16B** is to be coupled to the drive shaft **105** of the printer body **100**. The input spool **16** is rotated by the drive shaft **105**.

(Output Gear)

45 The output gear **18** may be a single gear for outputting, to the outside, a driving force for conveying the to-be-printed tape **11A**.

Specifically, the output gear **18** outputs a driving force to 50 the platen gear **104** of the printer body **100**. A rotation axis **L7** of the output gear **18** is parallel to the rotation axis **L5** of the second feed spool **15**. The output gear **18** overlaps a cover portion **32B** in the up-down direction.

The output gear **18** is partially exposed to the head 55 opening **33B**. The output gear **18** is in engagement with the platen gear **104** at the head opening **33B** in a state where the printing cassette **10** is mounted on the printer body **100**.

The second feed spool **15**, the output gear **18**, and the first roll **11** are disposed in the order of the second feed spool **15**, 60 the input gear **18**, and the first roll **11** in the up-down direction. That is, the output gear **18** is located between the second feed spool **15** and the first roll **11** in the up-down direction.

(Input Gear)

65 The input gear **19** is indirectly connected to the output gear **18** via the idle gear **20** and transmits, to the output gear **18**, a driving force input thereto from the printer body **100**.

The input gear 19 includes a gear 19A and a cylindrical spool 19B. The spool 19B is fixed to a surface of the gear 19A orthogonal to a rotation axis of the gear 19A and has spline teeth on an inner peripheral surface thereof. The gear 19A rotates integrally with the spool 19B by a driving force input to the spool 19B.

A rotation axis L8 of the input gear 19 (i.e., the rotation axis of the gear 19A and a rotation axis of the spool 19B) is coaxial with the rotation axis L6 of the input spool 16. A portion of the spool 19B is inserted in the input spool 16. The input spool 16, a portion of the input gear 19 (i.e., the gear 19A) and the first roll 11 are disposed in the order of the input spool 16, the portion of the input gear 19 (i.e., the gear 19A), and the first roll 11 in the up-down direction.

The rotation axis L8 of the input gear 19 is coaxial with the hollow portion of the input spool 16 in the up-down direction. Thus, the drive shaft 105 is inserted into the input spool 16 and the spool 19B of the input gear 19 simultaneously. As a result, although the input gear 19 is not directly coupled to the input spool 16, the input gear 19 is rotated by a driving source (i.e., the drive shaft 105) common to the input spool 16.

(Idle Gear)

The idle gear 20 is engaged with the input gear 19 and the output gear 18. The idle gear 20 transmits, to the output gear 18, a driving force input to the input gear 19.

The idle gear 20 may be a stepped gear in which a larger gear 20A engaged with the input gear 19 and a smaller gear 20B engaged with the output gear 18 are arranged coaxially. The smaller gear 20B has a diameter smaller than the larger gear 20A.

Further, the smaller gear 20B is disposed at a position closer to the first roll 11 than the larger gear 20A to the first roll 11 in the up-down direction (i.e., on an upper side). The idle gear 20 constitutes a deceleration mechanism that decelerates the driving force input to the input gear 19.

(Case)

The first case portion 31 serves as an upper end portion of the printing cassette 10. The first frame portion 32 is disposed below the first case portion 31 and is connected to the first case portion 31 in the up-down direction. The second frame portion 33 is disposed below the first frame portion 32 and is connected to the first frame portion 32 in the up-down direction. The second case portion 34 serves as a lower end portion of the printing cassette 10. The second case portion 34 is connected to the second frame portion 33 in the up-down direction.

The first case portion 31 and the first frame portion 32 accommodate the first roll 11. That is, the first roll 11 is disposed in a space surrounded by the first case portion 31 and the first frame portion 32.

The second case portion 34 and the second frame portion 33 accommodate the second roll 14, the second feed spool 15, and the input spool 16. That is, the second roll 14, the second feed spool 15, and the input spool 16 are disposed in a space surrounded by the second case portion 34 and the second frame portion 33.

A particular portion of the output gear 18, the input gear 19, and the idle gear 20 are disposed in a space surrounded by the first frame portion 32 and the second frame portion 33.

As illustrated in FIG. 3C, the first case portion 31 has an obverse surface 31A and the opening 31B. The obverse surface 31A is orthogonal to the up-down direction. The opening 31B is provided at the obverse surface 31A. The pressed portion 50 penetrates the first case portion 31 in the up-down direction.

As illustrated in FIGS. 5 and 6A, the first frame portion 32 includes a first sidewall 32A, the cover portion 32B, a first guide 32C, a first gear shaft 32D, a second gear shaft 32E, a third gear shaft 32F, a connecting portion 32G, and a second support wall 32H.

The first sidewall 32A defines side surfaces of the printing cassette 10. The side surfaces of the printing cassette 10 extend parallel to the up-down direction.

The cover portion 32B has a surface orthogonal to the up-down direction. The cover portion 32B is disposed at a position where the cover portion 32B overlaps the output gear 18 in the up-down direction. In the illustrative embodiment, the cover portion 32B is disposed at a right front corner of the first frame portion 32.

The first gear shaft 32D supports the output gear 18 rotatably. The second gear shaft 32E supports the input gear 19 rotatably. The third gear shaft 32F supports the idle gear 20 rotatably. The first gear shaft 32D, the second gear shaft 32E, and the third gear shaft 32F each protrude downward from a lower surface of the second support wall 32H.

The connecting portion 32G connects between the third gear shaft 32F and the pressed portion 50 in the up-down direction. In the illustrative embodiment, the connecting portion 32G, the third gear shaft 32F, and the pressed portion 50 are integral with each other.

The second support wall 32H is disposed between the first case portion 31 and the first support wall 33E of the second frame portion 33 in the up-down direction. The second support wall 32H has a support surface 32I that supports the first roll 11 from the idle gear 20 side (i.e., from below) in the up-down direction.

As illustrated in FIG. 7, the first guide 32C may be a portion around which the to-be-printed tape 11A drawn from the first roll 11 is wound. The first guide 32C has a plurality of ribs being plates that are apart from each other in a circumferential direction of the first roll 11. The plurality of ribs protrude in a radial direction of the first roll 11, and a protruding amount of each of the plurality of ribs (i.e., a plate width) increases as each of the plurality of ribs extends downward.

As illustrated in FIGS. 5 and 6B, the second frame portion 33 includes a second sidewall 33A, the head opening 33B, an outlet 33C, a second guide 33D, a first support wall 33E, and a restricting portion 33F.

The second sidewall 33A defines side surfaces of the printing cassette 10. The side surfaces of the printing cassette 10 extend parallel to the up-down direction.

The head opening 33B is a cutaway portion of the second sidewall 33A. The head opening 33B is a space in which the print head 102 is located by insertion into the head opening 33B from below in a state where the printing cassette 10 is mounted on the printer body 100. The head opening 33B opens downward in the printing cassette 10.

The second guide 33D is a portion around which the to-be-printed tape 11A that has passed the first guide 32C. As with the first guide 32C, the second guide 33D has a plurality of ribs being plates that are apart from each other in a circumferential direction of the second roll 14. The plurality of ribs protrude in a radial direction of the second roll 14, and a protruding amount of each of the plurality of ribs (i.e., a plate width) decreases as each of the plurality of ribs extends downward.

The first support wall 33E is disposed opposite to (i.e., below) the pressed portion 50 with respect to the idle gear 20 in the up-down direction. Further, the second case portion 34 is disposed opposite to the idle gear 20 with respect to the first support wall 33E in the up-down direction.

The first support wall 33E restricts downward movement of the third gear shaft 32F. As illustrated in FIG. 6B, the first support wall 33E has a protruding portion 33G. The protruding portion 33G may be a cross-shaped protrusion protruding upward.

A lower end of the third gear shaft 32F is slightly spaced from the protruding portion 33G. When a downward force is applied to the third gear shaft 32F, the third gear shaft 32F contacts the protruding portion 33G. In other words, when a downward force is applied to the third gear shaft 32F, the first support wall 33E supports the third gear shaft 32F from below and restricts a downward movement of the third gear shaft 32F.

As illustrated in FIG. 5, the restricting portion 33F is disposed between the first support wall 33E and the second case portion 34 in the up-down direction. The restricting portion 33F is disposed at a position where the restricting portion 33F overlaps the third gear shaft 32F in the up-down direction.

When a downward force is applied to the first support wall 33E, a lower end of the restricting portion 33F contacts the second case portion 34, whereby the restricting portion 33F restricts warping of the first support wall 33E in a direction toward the second case portion 34 (i.e., downward). The restricting portion 33F of the illustrative embodiment may be a cylinder that protrudes downward from the first support wall 33E and whose central axis is parallel to the up-down direction.

<Positional Relationship of Third Gear Shaft>

The third gear shaft 32F is inserted through the idle gear 20 and extends in the up-down direction parallel to a rotation axis L9 of the idle gear 20.

As illustrated in FIGS. 8A and 8B, the idle gear 20 has a sliding portion 20C, a first surface 20D, and a second surface 20E. The third gear shaft 32F is inserted in the sliding portion 20C and slides therein. The first surface 20D and the second surface 20E are orthogonal to the up-down direction. The first surface 20D may be a lower surface of the larger gear 20A. The second surface 20E may be an upper surface of the smaller gear 20B and is farther from the first support wall 33E than the first surface 20D from the first support wall 33E.

A dimension D1 of the third gear shaft 32F in the up-down direction is greater than a dimension D2 of the sliding portion 20C of the idle gear 20 in the up-down direction. The dimension D1 of the third gear shaft 32F in the up-down direction refers to a distance from a proximal end of the third gear shaft 32F (i.e., a portion connected to the second support wall 32H) to a distal end of the third gear shaft 32F.

The third gear shaft 32F penetrates both the first surface 20D and the second surface 20E of the idle gear 20. That is, the third gear shaft 32F protrudes downward relative to the second surface 20E of the idle gear 20.

The first roll 11 is disposed offset to the pressed portion 50 and at a position farther from the first support wall 33E than the idle gear 20 from the first support wall 33E in the up-down direction (i.e., a position closer to the pressed portion 50 than the idle gear 20 to the pressed portion 50). Further, at least a portion of the third gear shaft 32F overlaps the hollow portion of the first roll 11 in the up-down direction.

At least a portion of the connecting portion 32G overlaps the hollow portion of the first roll 11 in the left-right direction and the front-rear direction. Further, the first roll 11 and the first feed spool 12 are disposed around the connecting portion 32G. That is, the connecting portion 32G constitutes a shaft of the first feed spool 12.

The pressed portion 50 is disposed at a position closer to the obverse surface 31A of the first case portion 31 than the support surface 321 to the obverse surface 31A in the up-down direction. Further, the pressed portion 50 overlaps the opening 31B in the up-down direction. In the illustrative embodiment, the pressed portion 50 protrudes slightly above the obverse surface 31A.

As illustrated in FIG. 9, the third gear shaft 32F overlaps at least a portion of the pressed portion 50 in the up-down direction. Further, the rotation axis L9 of the idle gear 20 passes through the pressed portion 50.

At least a portion of a contact area A where the pressed portion 50 and the pressing member 121 are contacted with each other (i.e., an area where an external member that transmits a pressing force to the pressed portion 50 contacts the pressed portion 50) overlaps the third gear shaft 32F in the up-down direction. In the illustrative embodiment, the pressing member 121 has a cylindrical shape. Thus, the contact area A is circular.

Further, at least a portion of the pressed portion 50 overlaps the restricting portion 33F in the up-down direction. At least a portion of the restricting portion 33F overlaps the third gear shaft 32F in the up-down direction.

<Conveyance of Tape>

As illustrated in FIG. 9, the to-be-printed tape 11A and the ink ribbon 14A extend across the head opening 33B in the right-left direction. The to-be-printed tape 11A on which printing has been performed is discharged to the outside of the printer 1 from the outlet 33C. A portion of the output gear 18 is located in the head opening 33B. Further, the cover portion 32B is exposed to the head opening 33B.

As illustrated in FIGS. 10A, 10B, 10C, and 10D, the first guide 32C and the second guide 33D define a path through which the to-be-printed tape 11A constituting the first roll 11 is fed from the first frame portion 32 to the second frame portion 33.

Specifically, as illustrated in FIG. 10A, the to-be-printed tape 11A drawn from the first roll 11 is conveyed in a spiral manner toward the lower rear in the first frame portion 32 while contacting the first guide 32C from an outer side in the radial direction of the first roll 11. As illustrated in FIG. 10B, the to-be-printed tape 11A is further conveyed toward the lower left while extending across a connected portion of the first frame portion 32 and the second frame portion 33 in the up-down direction.

As illustrated in FIG. 10C, the to-be-printed tape 11A that has reached the second frame portion 33 is conveyed toward the lower front with contacting the second guide 33D from the outer side in the radial direction. As illustrated in FIG. 10D, the to-be-printed tape 11A that has reached the lower end portion of the printing cassette 10 passes the head opening 33B and is then discharged from the outlet 33C.

<Tape Conveyance and Printing by Printer Body>

The print head 102 performs printing on the to-be-printed tape 11A held by the printing cassette 10.

The print head 102 is disposed such that, in a state where the printing cassette 10 is mounted on the printer body 100, the print head 102 overlaps the to-be-printed tape 11A and the ink ribbon 14A in the front-rear direction at the head opening 33B.

The to-be-printed tape 11A that has been conveyed to the head opening 33B by the platen roller 103 is pressed toward the print head 102 in which the heating elements have generated heat, via the ink ribbon 14A. Thus, some ink on a particular surface of the ink ribbon 14A is transferred onto

11

the to-be-printed tape 11A, and characters, symbols, and other representations are printed on the to-be-printed tape 11A.

The platen roller 103 conveys the to-be-printed tape 11A from the inside to the outside of the printing cassette 10. The platen roller 103 contacts and presses the to-be-printed tape 11A toward the print head 102 at the head opening 33B.

The platen gear 104 is connected to the platen roller 103 and is to be engaged with the output gear 18. The platen roller 103 and the platen gear 104 are swingable between a position illustrated in FIG. 11 where the platen roller 103 and the platen gear 104 are spaced from the printing cassette 10 and a position illustrated in FIG. 12 where the platen gear 104 is in engagement with the output gear 18.

The drive shaft 105 is engaged with the input gear 19 when the drive shaft 105 is inserted into the input spool 16, and rotates the input spool 16 and the input gear 19.

As illustrated in FIG. 12, in a state where the printing cassette 10 is mounted on the printer body 100, the drive shaft 105 is in engagement with the input gear 19 and the platen gear 104 is in engagement with the output gear 18. Specifically, the drive shaft 105 is inserted into the input spool 16 and the input gear 19 of the printing cassette 10. Thereafter, the platen roller 103 and the platen gear 104 are swung toward the head opening 33B of the printing cassette 10.

As the input gear 19 is rotated by the drive shaft 105 in a state where the printing cassette 10 is mounted, the output gear 18 is rotated, the platen gear 104 is rotated by the rotation of the output gear 18, and the platen roller 103 is rotated by the rotation of the platen gear 104.

<Positional Relationship Between Printing Cassette and Housing>

As illustrated in FIGS. 13A, 13B, 13C, 13D, and 13E, the first surface 111 of the housing 110 has a first area 112, a second area 113, a third area 114, and a fourth area 115, each of which is adjacent to the cassette mounting opening 110A.

The first area 112 is located further to the front than the cassette mounting opening 110A. The second area 113 is located further to the rear than the cassette mounting opening 110A. That is, the second area 113 is located across the cassette mounting opening 110A from the first area 112 in the front-rear direction.

The third area 114 is located further to the right than the cassette mounting opening 110A. The fourth area 115 is located further to the left than the cassette mounting opening 110A. That is, the fourth area 115 is located across the cassette mounting opening 110A from the third area 114 in the right-left direction. The third area 114 and the fourth area 115 are located between the first area 112 and the second area 113 in the front-rear direction.

The first area 112, the second area 113, the third area 114, and the fourth area 115 of the first surface 111 constitute a peripheral area surrounding the cassette mounting opening 110A around a central axis parallel to the up-down direction. The first area 112, the second area 113, the third area 114, and the fourth area 115 are located upstream from (i.e., above) the print head 102 in a direction in which the printing cassette 10 is mounted to the housing 110.

As illustrated in FIG. 13C, the first area 112, the second area 113, and the print head 102 are located at respective positions such that a virtual plane S extending parallel to the first direction passes through the first area 112, the second area 113, and the print head 102, the virtual plane.

As illustrated in FIG. 13A, in a state where the printing cassette 10 is mounted on the housing 110, a particular portion of the printing cassette 10 adjacent to the first area

12

112 (i.e., the first side-surface 35A of the case 35) is located outside (i.e., above) the housing 110 beyond the first area 112 in the up-down direction.

As illustrated in FIG. 13E, in a state where the printing cassette 10 is mounted on the housing 110, another particular portion of the printing cassette 10 adjacent to the second area 113 (i.e., the second side-surface 35B of the case 35) is located outside (i.e., above) the housing 110 beyond the second area 113 in the up-down direction.

As illustrated in FIG. 13D, in a state where the printing cassette 10 is mounted on the housing 110, another particular portion of the printing cassette 10 adjacent to the third area 114 (i.e., the third side-surface 35C of the case 35) is located outside (i.e., above) the housing 110 beyond the third area 114 in the up-down direction.

As illustrated in FIG. 13B, in a state where the printing cassette 10 is mounted on the housing 110, another particular portion of the printing cassette 10 adjacent to the fourth area 115 (i.e., the fourth side-surface 35D of the case 35) is located outside (i.e., above) the housing 110 beyond the fourth area 115 in the up-down direction.

In a state where the printing cassette 10 is mounted on the housing 110, the printing cassette 10 protrudes outside (i.e., above) the housing 110 beyond the first area 112, the second area 113, the third area 114, and the fourth area 115 in the up-down direction.

In addition, in a state where the printing cassette 10 is mounted on the housing 110, at least a portion (i.e., an upper portion) of the first side-surface 35A and at least a portion (i.e., an upper portion) of the second side-surface 35B of the case 35 do not overlap the housing 110 in the front-rear direction.

In a state where the printing cassette 10 is mounted on the housing 110, the entirety of the first case portion 31 and an upper portion of the first frame portion 32 are located above the first area 112 and the second area 113. That is, at least a portion of the first roll 11 is located above the first area 112 and the second area 113.

The outlet 33C for the to-be-printed tape 11A is located inside the housing 110. Thus, in a state where the printing cassette 10 is mounted on the housing 110, the to-be-printed tape 11A is conveyed in the case 35 in a direction toward the inside of the housing 110 (i.e., downward) with respect to the first area 112 and the second area 113 in the up-down direction.

In a state where the printing cassette 10 is mounted on the housing 110, the entirety of the second frame portion 33 and the entirety of the second case portion 34 are located below the first area 112 and the second area 113. That is, the second roll 14 is located below the first area 112 and the second area 113. The output gear 18 is also located below the first area 112 and the second area 113.

[1-2. Effects]

According to the illustrative embodiment described in detail above, the following effects may be obtained.

(1a) In a state where the printing cassette 10 is mounted on the housing 110, the particular portion of the printing cassette 10 is located outside the housing 110 beyond the first surface 111. Thus, the printing cassette 10 may be held and removed from the housing 110 without a tab. As a result, an increase in cost of the printing cassette 10 may be avoided.

(1b) The output gear 18 is located below the first area 112 and the second area 113 in a state where the printing cassette 10 is mounted on the housing 110. Thus, the particular portion of the printing cassette 10 may be located outside the

housing 110 beyond the first surface III while a driving force from the output gear 18 is transmitted to the platen gear 104.

2. Second Illustrative Embodiment

[2-1. Configuration]

A printer 1A illustrated in FIGS. 14A and 14B includes a printing cassette 10A and a printer body 10A.

In FIGS. 14A and 14B, a cover and a pressing member of the printer body 100A are not illustrated. The pressing member of the printer body 100A may be identical to the pressing member 121 of the printer body 100 of FIG. 1A.

<Printing Cassette>

The printing cassette 10A includes a third roll 21, a take-up spool 22, a take-up gear 23, and a pinch roller 24, each of which are illustrated in FIG. 15, in addition to the components of the printing cassette 10 of the first illustrative embodiment, and further includes an input spool 25, a first case portion 36, a first frame portion 37, a second frame portion 38, and a second case portion 39 as alternatives to the input spool 16, the first case portion 31, the first frame portion 32, the second frame portion 33, and the second case portion 34 of the printing cassette 10 of the first illustrative embodiment.

The input spool 25 may be identical to the input spool 16 except that the input spool 25 does not have the spline teeth 16B. The first case portion 36, the first frame portion 37, the second frame portion 38, and the second case portion 39 may be identical to the first case portion 31, the first frame portion 32, the second frame portion 33, and the second case portion 34 that are further extended in the right-left direction, respectively. The other configurations of the printing cassette 10A may be the same as those of the printing cassette 10 of the first illustrative embodiment except for the points described below, and thus a description thereof will be omitted.

In the third roll 21, a laminating tape used for protecting the to-be-printed tape 11A is wound around the input spool 25. The laminating tape has an adhesive surface to be adhered to the to-be-printed tape 11A on which printing has been performed by the print head 102.

The take-up spool 22 is rotatable about its rotation axis L10. The rotation axis L10 of the take-up spool 22 is parallel to the rotation axis L5 of the second feed spool 15 (i.e., the up-down direction). The take-up spool 22 takes up the ink ribbon 14A by rotation of the take-up gear 23.

The take-up gear 23 is connected to the take-up spool 22 and is in engagement with the idle gear 20. The take-up gear 23 is rotated by a driving force input to the input gear 19 and rotates the take-up spool 22.

The pinch roller 24 presses the laminating tape toward the to-be-printed tape 11A on which printing has been performed, in cooperation with a pressing roller 106. The pinch roller 24 is disposed downstream from the head opening 33B in a conveyance direction of the to-be-printed tape 11A.

<Printer Body>

The printer body 100A may be identical to the printer body 100 of the first illustrative embodiment to which the pressing roller 106 illustrated in FIG. 16 is added. The other configurations of the printer body 100A may be the same as those of the printer body 100 of the first illustrative embodiment except for the points described below, and thus a description thereof will be omitted.

The pressing roller 106 is configured to be swingable together with the platen roller 103 and the platen gear 104. That is, the pressing roller 106 is swingable between a position illustrated in FIG. 16 where the pressing roller 106

is spaced from the printing cassette 10A and a position illustrated in FIG. 17 where the pressing roller 106 presses the to-be-printed tape 11A and the laminating tape in cooperation with the pinch roller 24.

5 [2-2. Effects]

According to the illustrative embodiment described in detail above, the following effects may be obtained.

(2a) While having the same advantages as those of the first illustrative embodiment, contents printed on the to-be-printed tape 11A may be protected by the laminating tape.

3. Other Illustrative Embodiments

15 Although the illustrative embodiments of the disclosure have been described above, it is needless to say that the disclosure is not limited to the above-described illustrative embodiments and may adopt various embodiments.

(3a) The printers of the above-described illustrative embodiments are not limited to printers that perform printing using an ink ribbon. The printers may use a heat-sensitive sheet that is a continuous strip as an alternative to the to-be-printed tape of the first illustrative embodiment, and a laminating tape (i.e., a protective tape) as an alternative to the ink ribbon of the first illustrative embodiment.

20 Further, the printers may use, as a to-be-printed tape, a stencil tape on which a printing pattern is to be perforated by a thermal head, and as a second tape, a slip sheet that is a continuous strip for protecting and supporting the stencil tape. In this case, at a head opening, the to-be-printed tape may be laid on the slip sheet at a position closer to a print head than the slip sheet to the print head (i.e., as an upper layer) or at a position farther from the print head than the slip sheet from the print head (i.e., as a lower layer).

25 (3b) The printing cassettes of the above-described illustrative embodiments are not limited to a printing cassette in which a first roll, an output gear, and a roll (i.e., a second roll or a third roll) of an auxiliary tape to be used for printing or protecting a to-be-printed tape are arranged in the up-down direction. In the printing cassette, the first roll may be disposed overlapping the second roll or the third roll in a direction orthogonal to the up-down direction.

30 (3c) The printing cassettes of the above-described illustrative embodiments may include two or more idle gears. Further, the idle gear might not necessarily be a stepped gear, and may be a single gear. Further, the printing cassette may not necessarily have an idle gear, and the output gear may be directly engaged with the input gear.

35 (3d) The printing cassette of the second illustrative embodiment may include a third feed spool around which a laminating tape is wound as an alternative to the take-up spool. In the printing cassette according to the second illustrative embodiment, the input spool may be used as a take-up spool for an ink ribbon.

40 (3e) The functions of a single component in the above-described illustrative embodiments may be achieved by multiple components, or the functions of respective multiple components may be achieved by a single component. Further, some of the configurations of the above-described illustrative embodiments may be omitted. In addition, at least some of the configurations of one or more of the above-described illustrative embodiments may be added to or replaced with the configurations of another embodiment.

45 It should be noted that all aspects included in the technical idea specified by the wording described in the claims are embodiments of the disclosure.

15

What is claimed is:

1. A printer comprising:
a housing having a first surface having a cassette mounting opening;
a print head disposed in the housing, the print head extending toward the cassette mounting opening from an inside of the housing;
a platen roller disposed in the housing, the platen roller facing the print head; and
a printing cassette mountable on the housing by insertion to the cassette mounting opening in a first direction, wherein:
the first surface has:
a first area adjacent to the cassette mounting opening; and
a second area adjacent to the cassette mounting opening, the second area being opposite to the first area with respect to the cassette mounting opening in a second direction orthogonal to the first direction, the first area and the second area are located upstream from the print head in a direction in which the printing cassette is mounted to the housing, and
in a state where the printing cassette is mounted on the housing, a portion of the printing cassette adjacent to the first area is located outside the housing beyond the first area in the first direction and a portion of the printing cassette adjacent to the second area is located outside the housing beyond the second area in the first direction.
2. The printer according to claim 1, wherein:
the printing cassette includes a first roll into which a printing tape is wound, and
in a state where the printing cassette is mounted on the housing, at least a portion of the first roll is located outside the housing beyond the first area and the second area.
3. The printer according to claim 2, wherein:
the printing cassette includes a case accommodating the first roll, and
in a state where the printing cassette is mounted on the housing, the printing tape is conveyed in the case in a direction toward an inside of the housing with respect to the first area and the second area in the first direction.
4. The printer according to claim 1, wherein:
the printing cassette includes a second roll into which an ink ribbon is wound, and
in a state where the printing cassette is mounted on the housing, the second roll is located within a range of the housing not beyond the first area and the second area in the first direction.
5. The printer according to claim 1, wherein:
the printing cassette includes a gear configured to transmit a driving force, and
in a state where the printing cassette is mounted on the housing, the gear is located within a range of the housing not beyond the first area and the second area in the first direction.
6. The printer according to claim 1, wherein:
the first surface further has a third area and a fourth area, both of which are adjacent to the cassette mounting opening, the third area and the fourth area being located between the first area and the second area in the second direction,

16

the fourth area located opposite to the third area with respect to the cassette mounting opening in a third direction orthogonal to the first direction and the second direction, and

in a state where the printing cassette is mounted on the housing, a portion of the printing cassette adjacent to the third area is located outside the housing beyond the third area in the first direction and a portion of the printing cassette adjacent to the fourth area is located outside the housing beyond the fourth area in the first direction.

7. The printer according to claim 1, further comprising a cover being openable and closable with respect to the housing,

wherein the cover contacts the first surface when the cover is closed.

8. The printer according to claim 1, wherein the print head and the platen roller face each other in the second direction.

9. The printer according to claim 1, wherein the first area, the second area, and the print head are located at respective positions such that a virtual plane passes through the first area, the second area, and the print head, the virtual plane extending parallel to the first direction.

10. A printer comprising:

a housing having a first surface having a cassette mounting opening;

a print head disposed in the housing, the print head extending toward the cassette mounting opening from an inside of the housing;

a platen roller disposed in the housing, the platen roller facing the print head; and

a printing cassette mountable on the housing by insertion to the cassette mounting opening in a first direction, wherein:

the first surface has:

a first area adjacent to the cassette mounting opening; a second area adjacent to the cassette mounting opening, the second area being opposite to the first area with respect to the cassette mounting opening in a second direction orthogonal to the first direction,

the first area and the second area are located upstream from the print head in a direction in which the printing cassette is mounted to the housing, and
in a state where the printing cassette is mounted on the housing, the printing cassette protrudes outside the housing beyond the first area and the second area in the first direction.

11. A printer comprising:

a housing having a first surface having a cassette mounting opening;

a print head disposed in the housing, the print head extending toward the cassette mounting opening from an inside of the housing;

a platen roller disposed in the housing, the platen roller facing the print head; and

a printing cassette mountable on the housing by insertion to the cassette mounting opening in a first direction, wherein:

the printing cassette has a first side-surface and a second side-surface overlapping each other in a second direction orthogonal to the first direction, and
in a state where the printing cassette is mounted on the housing, at least a portion of the first side-surface and at least a portion of the second side-surface do not overlap the housing in the second direction.

* * * * *
